Application November 7, 1939, Serial No. 303,207

10 Claims. (Cl. 209—18)

This invention relates to classifiers that are used in the art of classification, that is, in the treatment of suspended solids making use of their different settling rates to effect a separation thereof into at least two fractions divided in so far as possible, in accordance with a predetermined particle size. An ideal arrangement would be to have all particles over a critical size go into one fraction, with all particles under that size going into another fraction. Classifiers, as most frequently used in metallurgy, comprise a tank that holds liquid-solids mixture or pulp being treated. The tank is generally provided with an inclined partially-submerged floor along which the fraction of larger and more readily settleable of the suspended solids, called sands, is conveyed upwardly to emergence and discharge. The fraction of finer solids that remain in suspension is overflowed from the other or deep end of the classifier.

Classifiers of this type are often used in what is called closed circuit grinding. In this operation, ore after being crushed is supplied to a grinding mill, the discharge from which has particles fine enough to be treated for the recovery therefrom of metal values, but also has particles too large for such treatment. Therefore, it is the function of a classifier to receive this conglomerate discharge and by the classifier's size selective or fractionating functions, overflow of fine particles or fines on their way to value-recovery treatment, while emerging to discharge all particles larger than the usable sizes. These large particles or sands, are returned to the mill for regrinding until they are reduced to usable particle size. The selectivity of a classifier becomes important because if it does not dependably reject all sands from the fines overflow, subsequent treatment of the fines is interfered with; and if fines are not prevented from contaminating the discharged sands, the mill to which the sands are returned for regrinding will otherwise be called upon to do useless work in grinding further the fines that are already fine enough. However, the selectivity or fractionating ability of a classifier is important when it is used in other industries, such as in the washing and classifying of sand for use in concrete and the like. So a major object of this invention is to devise a classifier and a method of operation thereof that will attain efficient control of particle-size separation.

Present-day classifiers, as now designed and operated, are incapable of making efficient coarse classifications; that is, in the range from 4 to 28

mesh or so. It is possible to make these coarse classifications or segregations, but with the limitations of the machines now available, it is necessary to do this at a very high density, namely, 5 in a very thick pulp. The reason why this is so is that the mechanical limitations of the mechanism used for removing the oversize from the classifier are such that the size of unit is so great that the overflow capacity of the machine is out 10 of all proportion to the raking capacity, with the result that if an attempt is made to make a coarse separation in a dilute pulp, the particles settle so fast that the desired size cannot be overflowed. As a result of this, it is customary 15 to thicken up the pulp until the settling rate has been retarded to such an extent as to adjust the overflow capacity to the dimensions dictated by the mechanism.

Effecting the classification at a high density or 20 in a thick pulp has the very definite objection that it results in a very inefficient classification. The reason for this is that in addition to the contamination of the oversize product, resulting from the simultaneous settlement of fine particles 25 along with the coarse particles, there is an additional contamination resulting from the pulp that fills the voids between the particles of oversize product. This pulp must contain at least as many fine particles as are contained in the pulp 30 overflow, since the overflow is the most dilute pulp in the machine.

An idea of the magnitude of this contamination of oversize product with material that should have overflowed, is indicated in the following 35 table, compiled and interpolated from analyses of active classifier operations:

TABLE I
Percentage of rake which is really overflow

	Percent solids in overflow	Percent solids in rake	Percent of rake which is overflow	Approximate percent+mesh of separation*
45	10	74	3.9	69
	20	76	7.8	65
	30	78	12.0	61
	40	79	17.7	55
	50	80	24.8	48
	60	81	35.0	38
50	65	82	40.8	32

*At 3:1 circulating load.

It might be pointed out that in the coarse-separation range being dealt with here, present practice is to make the separations at from 50% to 65% solids; whereas it is possible with this

new machine to effect the separations at any dilution, and with the present milling practice it will be possible to use dilutions of about 20% to 40% solids.

Therefore, what I set out to develop was a machine that would make coarse separations at high dilutions. To do this, I found it advantageous to use relatively small classification or overflow areas compared with the dimensions required to accommodate a raking or discharging mechanism capable of handling the very tremendous tonnage of sand that will settle out in this small overflow area. I conceived the idea of trying to divorce the two functions of the machine. This I do in a tank which can accommodate the necessary raking or sand-dewatering mechanism, and associating with it a classifying chamber that contains a pool of small but adjustable dimensions. The area or overflow velocity can be adjusted to give the desired separation without regard to the size of tank required to accommodate the discharging and dewatering device.

In the preferred embodiment the two compartments are in constant hydraulic communication through a slot of relatively small area. Classification is effected in the pool of the top compartment. The sand discharged from the pool through the slot is removed without any further classification. The raking mechanism does a dewatering job, and the surplus water rises through the slot to overflow from the pool.

In present-day classifiers there are provided in the tank, and over the inclined bottom floor, three general types of conveyors for urging settling sands upward along the floor, namely, a spiral screw conveyor, flights carried by endless belts or chains travelling unidirectionally, and reciprocating rakes, the latter being frequently referred to as the Dorr type. In such classifiers, all of the material to be classified is supplied to the tank, from which all of the suspended solids must be gotten out, whereas it is a feature of this invention to subject the material to be classified to a particle-size selective or fractionating treatment comprised in a relatively small pool outside of and exterior to the tank proper, with the area of the pool being adjustable. This is done by rapidly flowing through said pool the feed material to be classified at a rate whereby a substantial percentage of the liquid with the finer solids suspended therein will pass substantially horizontally over a submerged slot in a covered top section of the classifier tank. When safeguarded by suitable mechanical and hydraulic controls, the fines in the feed tend to hurdle the slot while the quicker-settling coarser-sized particles drop through the slot into the classifier tank from which they are dewatered by being raked to emerged discharge as is usual. It is the keeping of the major portion of the fines out of the bath in the classifier tank proper that constitutes the foundation upon which this invention is built, and the arrangement and control of the hurdle constitutes an important feature of the invention.

Whether any particular particle in suspension in the feed sinks through the slot into the classifier bath, or instead flows rushing past the submerged slot and thus avoids entering the classifier, is determined by certain control features that relate to the pool on the covered top or deck of the classifier. These features comprise generally the correlating of the pool area or velocity of overflow therefrom, and the dimensions of the submerged slot, to the end that finer solids are discouraged from passing therethrough. More spe-

cifically these features include one or more of the following: adjustability of the width of the slot (and also possibly of its length); adjustability of damming means on the side of the slot away from the feed; and, in some embodiments, adjustability of the amount of hydraulic lift provided to cause some upflow through the slot and consequent pulsations produced in the liquid upflowing through the submerged slot. Other factors that might be used to control the selectivity of the pool are (1) to dilute the bath in the tank by adding water; (2) to vary the rate of movement of the rakes in the classifier bath; and (3) to change the rate of feed; but the last two of these are not ordinarily desirable practically.

The invention possesses other objects and features of advantage, some of which, with the foregoing, will be set forth in the following description. In the accompanying drawings, for the purpose of example, there has been illustrated the best embodiment of the invention now known to me, but such embodiment is to be regarded as typical only of many possible embodiments, and the invention is not to be limited thereto.

In the drawings:

Fig. 1 is a vertical section through the lower or fines discharge end of a classifier of the Dorr type having and embodying the features of the present invention;

Fig. 2 is a perspective view at larger scale looking down on the end of the classifier of Fig. 1;

Fig. 3 is a fragmentary section taken on the line 3—3 of Fig. 1;

Fig. 4 is a diagrammatic view somewhat similar to Fig. 1 but showing the manner in which the invention operates to effect the desired classification.

As has been previously mentioned, the mechanical classifiers of the prior art make use of a relatively large tank within which operates conveying means which serves to urge settled material to a point of emergence and which also causes a certain amount of turbulence in the classifier bath, thus discouraging settling of the fine particles which overflow a suitable weir. These prior classifiers are quite efficient in making what are commonly known in the art as fine separations wherein the product that is desired is an overflow containing as much as possible of the finest size materials and as little as possible of coarser sizes. However, these classifiers have been generally incapable of producing efficiently at high dilution what is commonly termed as a coarse separation (say 4 to 28 mesh).

The classifier of the present invention is particularly adapted to perform the act of making what is known as a coarse separation in a highly efficient and satisfactory manner. Generally speaking, the arrangement of the classifier of the present invention comprises a relatively large tank having a sloping bottom or floor up which the settled sands are conveyed to emergence and dewatered by suitable conveying mechanism. The lower or discharge end of the classifier tank is covered and provided with means for the formation of a relatively small pool on the upper surface of the cover or deck so that all material treated by the machine must enter and flow through the small pool. The cover or deck is provided with a slot or opening communicating with the main tank. All feed entering the pool rushes through it in a rapid flow and the coarsest particles drop from the pool through the slot into the classifier tank, while substantially all other particles are carried by the rapid flow over and

past a suitable weir and discharged as overflow. The pool is located in what is frequently referred to as the classification compartment which increases in depth in passing from a feed receiving section thereof to the overflow region thereof. The slotted discharge leading therefrom for the downward passage of the larger or more readily settleable solids is from the deeper section of the classification compartment, or as otherwise expressed, is from the lower portion of the deeper section of the pool. The overflow of liquid with the finer solids therein is from an upper portion of the deeper section of the compartment or pool therein. Thus, the small pool of initial liquid body is in substantially vertical hydraulic communication with an underlying portion of a secondary liquid body that is in the classifier tank and performs functions of classification or segregation so that the tank itself serves primarily as a thickener or dewaterer wherein the coarse solids which have dropped through the slotted deck settle to the bottom and are conveyed upwardly to emergence by the conveying mechanism. In this embodiment apparently little classification or segregation takes effect within the classifier tank and substantially all particles once dropping through the slot become a part of the ultimately emerged sands or so-called raked product.

In another embodiment additional water is supplied to the classifier tank preferably by means of sprays directed upon the settled material near the point where it emerges from the classifier bath. In this embodiment, depending upon the amount of water supplied, there may be some upflow of liquid upwardly through the slot, thus assisting in the classification action and carrying up any fines which may have passed downwardly through the slot.

Referring particularly to the drawings, in Fig. 1 there will be seen the lower or overflow end of a classifier of the well-known Dorr type. This classifier comprises a tank having an upwardly inclined bottom or floor 5, end wall 6 and side walls 7. Raking blades 8 attached to stringers 9 are operatively supported in the tank by means which include the hanger 10, linkage 11 and bell crank 12. These details, and the supporting and driving arrangement at the upper end of the raking assembly, and their operation, are well known in the art and are thoroughly described and illustrated in the patent to J. V. H. Finney No. 1,997,379, so further description thereof is deemed unnecessary. Furthermore, according to the broader aspects of the invention, it will be understood that any other suitable type of conveying and dewatering mechanism may be utilized instead of the reciprocating rakes herein illustrated, for example, a spiral screw conveyor, a bucket elevator, sand wheel or endless belt or chain conveyor equipped with suitable blades.

In the present invention the lower end of the classifier tank is completely decked over or covered by means of a sloping roof or deck 13 which preferably, although not necessarily, parallels the inclined bottom or floor 5. The deck 13, at the discharge end of the classifier, preferably is extended beyond the end wall 6 and turns slightly downward as indicated at 14 to form a discharge lip for the classifier overflow. The deck 13 extends longitudinally and upwardly from the end wall 6 to a vertical transverse partition 18 extending the full width of the tank. The deck 13 is impervious and continuous except for a slotted area or region left at 26. The deck 13 and the vertical transverse partition 18 effectively sepa-

rate the liquid holding section of the tank from the regions above the deck except there is constant hydraulic communication through the slotted area between that portion of the liquid that is within the tank and underlying the inclined deck and the liquid-solids mixture flowing through and undergoing classification in the pool that is maintained on the inclined deck. The deck has a lower section 13a terminating at a suitable distance from the end wall 6 and is provided with a substantially vertical baffle or deflecting plate 15 extending downwardly into the tank and transversely of the tank. The deck also has an upper section 13b and side sections 13c. The transverse edges of the slot or slotted section 26 are defined by the upper and lower edge portions respectively of the lower deck section 13a and the upper deck section 13b. The longitudinal edges of the slot are defined by inwardly disposed edge portions of the side sections 13c of the deck.

A feed receiving space or section 17 is provided at the upper end of the deck between transversely spaced vertical walls 16. These vertical walls 16 extend from the partition 18 longitudinally the full length of the inclined deck 13 and are disposed at opposite sides of the slot or slotted portion 26. Secure and water-tight joints are provided at the lower edges of the wall 16 and the inclined deck 13 and at the vertically extending higher end portions thereof with the transverse partition 18. Thus, there is provided a longitudinally extending trough of progressively increasing depth. This trough is closed at its upper or feed receiving end by the transverse partition 18 and is left with the slotted area or section 26 intermediate its ends.

Each side 7 of the tank extends upwardly a substantial distance, to wit, to an elevation higher than that of the high end of the deck 13 whereby a liquid level may be maintained in the tank which is substantially higher than that of the flowing pool or body undergoing classification in what may be referred to as the primary classifying zone 28 that is located within the space provided by the U-shaped trough construction just referred to. This trough is functionally divided into three regions, zones, or areas disposed in serial arrangement as follows, to wit, into a feed receiving pocket or section 17 immediately over the high end of the inclined deck and therefore referred to as the high feed well section; a primary or initial liquid holding or classifying pool, zone or area 28 immediately over the intermediate section of the inclined deck wherein the slot or slotted portion 26 is located and therefore referred to as the intermediate zone, or area and which may be viewed as a zone lower than the feed receiving zone; and a sludge-way launder or slimes discharge flume immediately over the lower section of the inclined deck and which is therefore properly referred to as the low effluent launder or liquid discharge section leading from the apparatus. These three sections, zones, or areas are realized and established as follows:

A longitudinally extending and longitudinally positionable U-shaped member 35 is disposed within the trough, the exterior of this member is of such contour and size as to provide a sliding and nesting fit with the interior of the trough. This longitudinally positionable U-shaped member has at the high end thereof a vertically and transversely extending wall 21 which extends from the top portion of the member downwardly close to but so as to be vertically spaced from

the higher edge portion of the bottom section 27 of said member whereby a feed discharge area or passageway is left or provided at 22 for substantially the full width of the trough. This downwardly extending transverse wall or longitudinally adjustable partition member 21 as it may be called has at the lower end thereof a vertically positionable transverse gate 23 whereby the effective height or area of the feed discharge passage may be regulated. This transverse member or wall 21 serves as a longitudinally positionable wall of a feed receiving member or feed well 17 of which the other walls thereof are provided by the fixed or main transverse partition 18 and by said upper sections of the longitudinally extending trough walls 16. The area which is left open along the lower edge of the longitudinally adjustable transverse position serves as a horizontally and transversely extending feed discharge area leading from the high feed well to the high shallow end of the succeeding classifying pool or zone 28 and which is located on the opposite side of, and which is adjustable as to length by, the longitudinally adjustable transverse partition 21.

The opposite longitudinal extremity or deeper section of the classifying zone or pool 28 is defined by a vertically adjustable transversely extending partition 41 of which the uppermost edge 41a defines an overflow weir past which liquid from the classifying area with the finer solids therein cascades and rushes over into the sluice-way or effluent launder on its way from the apparatus. The vertically positionable weir member 41 is adjustably secured in place in any suitable manner as by bolts 41b extending through slotted portions in the baffle members 15 heretofore referred to. It will here be remarked that the baffle members 15 serve to deflect solids engaging therewith in their downward path from the classifying zone into the liquid underlying the classifying zone whereby there is avoided a delivery of gravitating solids into the extreme lowermost end of the deep tank section. This baffle or deflecting member 15 is shown in Fig. 2 as depending from the inclined deck 13 and as extending the full width of the tank, namely, from the longitudinal wall 7 at one side of the tank to the longitudinal wall 7 at the other side of the tank.

The adjustable U-shaped member 35 may be viewed as providing a bottom lining section 27 and side wall lining sections 29. As to said longitudinally adjustable member 35 it will be noted that the section 27 just referred to provides a floor portion immediately over and in substantial engagement with the inclined deck and this statement applies regardless as to its particular longitudinal position when disposed for the novel operation of the apparatus. From the lowermost edge of this adjustable floor portion 27 there depends a transversely extending lip 38 which extends downwardly through the slot of the inclined roof and it will be observed that by changing the longitudinal position of the U-shaped member 35 there is accomplished a corresponding change in the longitudinal dimensions of the slot.

Between this lip 38 and the adjustable vertical gate 23 which is thus provided by the U-shaped member, there is located, comparatively close to the gate 23, an upwardly extending flow impeding or jump baffle 37 provided for ironing out inequalities of distribution from the feed discharge opening referred to, whereby a more uni-

form transverse distribution will be effected of the liquid-solids pulp as it enters the classifying zone.

It has recently been ascertained that the classification or fractionating of solids as to certain desired groupings of particle-size is attainable by a relatively fast flow of liquid from the feed receiving pocket into and across the classification pool holding zone during which time only a desired type of solids of relatively heavy character will pass from the pool downwardly through the slot into the underlying portion of the tank while liquid with the finer solids therein will flow over and past the vertically positionable weir that controls the depth of the classifying pool.

It has also only recently been ascertained that desired classification is primarily a function of the area of the classifying pool or as otherwise expressed of the distance between the vertical plate or wall 21 that is between the feed receiving section 17 and the classifying zone 28 on the one hand and the overflow weir 41a at the opposite end of the classifying zone on the other hand. Normally the U-shaped member 35 is secured in place relative to the trough through the medium of clamping means 36 comprising clamping screws that engage outwardly projecting flange portions disposed at and along the upper edges of the trough wall 16. Primarily in order that the desired change in surface area or consequent length of flow across the classifying zone may be realized, the U-shaped member 35 and the parts thereof which are movable therewith, have been made so that longitudinal adjustment of all can be made preferably simultaneously. To attain a construction which will readily permit of the desired longitudinal adjustment there have been provided jack screws or lifting devices such as 39, which can be relied upon for forcibly effecting slight vertical movement of the U-shaped member relative to the U-shaped trough in which it is located. This vertical movement is sufficient to loosen any sand or other solids matter which might otherwise tend to bind the adjustable U-shaped member in the position occupied therefor and to lift it from any sands which may have become lodged in the underside thereof on the deck immediately thereunder. There are also provided longitudinal forcing and adjusting means such as screws 34 having right and left hand threaded sections at opposite ends thereof of which one of the sections has threaded engagement with the nut or socket member 32 fixed to the main side wall 16 of the trough, while the other end has engagement with a nut or socket member 33 that is secured to a flange or wall portion of the U-shaped member 35. Of course, after longitudinal adjustment has been effected the jack screws 39 or equivalent operating device should be positioned whereby the U-shaped member 35 will assume proper operative position therefor with respect to the underlying sections of the U-shaped member and whereby the screws of the clamping means 36 can be relied upon for securing the member 35 in its longitudinally adjusted position.

The vertical positioning of the weir member can be relied upon in obtaining the desired settling conditions within the apparatus as a whole and thereby indirectly attaining the type of classification or fractionation desired. This adjustment, however, is only secondary to that which is accomplished by the longitudinal adjustment of the U-shaped member and the consequent and direct adjustment in a longitudinal direction

of the partition 21 between the feed receiving well 17 on the one hand and the classifying area or zone on the other. It will also be noted that the transverse partition 21 has associated therewith along the lower edge portion thereof the vertically adjustable gate 23 which can be relied upon for regulating or controlling to a certain extent the quantity of feed passing from the feed receiving chamber into the classifying zone. The gate 23 is secured by bolts 24.

Fig. 4 of the apparatus can now well be referred to as illustrative of the settling or sedimenting conditions existing within the classifier during the normal operation thereof. The incoming pulp is first delivered into the feed receiving pocket 11, rushes in a longitudinal direction therefrom to the adjustable feed passage-way 22 into the classification zone 28. In this zone the baffle 37 provides a flow distributing wall on the opposite side of which there progressively form and collect bodies of solids that assume a shape or contour much after the order of the fine dots used on the drawings. They deposit longitudinally behind and ahead of the baffle 37. As the liquid flows through the classification zone, due to the controlled conditions therein, the larger and heavier solids sought to be separated pass downwardly in more or less sheet formation through the slotted area 26 left between the depending flange 38 and the overflow weir. The pulp in the classification pool 28 has a relatively high density—substantially higher than that of the liquid content in the underlying region of the tank, with the result that in the normal operation of the apparatus, the height of the level of the liquid within the tank is at an elevation indicated by B of Fig. 4 which is relatively high as compared with the general surface level A of the liquid in the classification pool 28. The general height or elevation of liquid or pulp in the feed receiving chamber 17 is sufficiently high as compared with that in the classifying pool so that a relatively high velocity of flow will at all times exist across the classifying pool 28.

At the most there is relatively little classification of solids within the raking compartment. The operation of the apparatus in the raking compartment is primarily as a solids removing and dewatering instrumentality. There may be a slight upflow of liquid from the raking compartment through the slot 26 upwardly into the classification zone 28 consequent to any supply of liquid which may be applied at the high end of the raking section for the purpose of further washing the sand and also consequent to any accumulation of water in the raking section incident to the dewatering operation performed therein. Because of the fact a relatively large part and in fact primarily the entire classifying operation is realized within and performed by the high flows of liquid as it passes through the horizontally adjustable classification pool 28; this is sometimes herein referred to as the primary or initial body of liquid, whereas the liquid of the tank is herein referred to as a secondary body of liquid.

In operating the classifier of the present invention it will be understood that the slidable trough 35 defined by the bottom member 27 and side walls 29 will be positioned by means of screws 34 at a suitable point so that the slot 26, actually measured by the distance from the baffle 15 to the lip 38, will be of a desired size or width. The vertically sliding gate 23 is also adjusted to

provide a proper size or height for the discharge opening 22 of the feed well or feed launder 17. The feed of suspended solids to be classified is continuously introduced into the feed receiving section or launder 17 by any suitable piping arrangement not shown, a suitable head of liquid being maintained within the launder. The feed suspension then flows through the opening 22 and across the jump baffle 37 in a relatively thin sheet, an object of the narrow opening 22 and the jump baffle 37 being to impart an even spread to or distribution of the feed. The suspension will then flow down the inclined sluice-way or trough defined between the longitudinally adjustable walls 29 and the fixed trough side wall 16 and pass through the slot 26 filling the lower part of the tank to form what is known as the bath. Since no opening for the escape of liquid is provided in the tank, the same will soon become filled and the continued feed of suspension will form a relatively small pool confined by the dam or weir 41a, the upwardly extending just referred to side walls and the end walls of the slidable trough or U-shaped member 35 extending back as far as the jump baffle 37. The continued feed of suspension will, of course, cause liquid to overflow the dam or weir 41a from the pool just referred to. The pool thus formed being relatively quite small compared to the volume or rate of feed, the suspension will rush through the pool at a relatively rapid rate. Only the largest and heaviest particles will drop out of this rush of suspension and pass through the slot 26 down into the classifier bath, all other particles passing rapidly with the overflow across the weir 41a where the material will flow down the deck section 13a and off the discharge lip 14 to any suitable destination. At the same time the sands conveying mechanism will be operated, in known manner, to cause the material which has fallen through the slot 26 and settled upon the bottom or floor 5 of the classifier tank to be conveyed upwardly along said bottom and ultimately discharged in dewatered condition at the upper end of the classifier.

Fig. 4 of the drawings illustrates the actual operation of the present classifier and the manner in which it functions to produce a clean and coarse sand product and overflow all that is possible of the fine and intermediate sized particles.

The pool as can be seen is maintained by a weir or dam on one side and a sloping deck on the other. Therefore, since the point of intersection of the pool surface with the sloping deck can be varied by varying the height of the weir, the area can be changed by the adjustment of the weir, and this is the main adjustment for the separation.

Besides restricting the area lengthwise, the area across the machine can also be restricted; in other words, the classification pool can be narrower than the width of the main tank or even that of the raking blades. The slot must be small enough to prevent mixing of the material in the classification pool with the communicating large body of water in the raking or discharging compartment; in other words, there probably must be restriction at this point, but the degree of restriction does not seem to effect the general result. Narrowing the slot has given somewhat better classification, probably due to preventing such intermixing.

In this figure the apparatus will be assumed to be in continuous operation with the blades 8 being reciprocated in known manner to convey settled

sands up to the inclined bottom of floor 5. Appropriate clearance is provided between the top deck 13 and the blade mechanism when in its uppermost position, a continuing supply of liquid containing solids of different sizes being introduced into the feed launder 17. The suspension escapes from the launder through the opening 22 and rushes rapidly over the jump baffle 37 which assists in spreading the flow into a thin and even sheet. This flow of solids and liquids into the pool established by the dam or weir member 41 causes a rapid current through the pool which overflows the weir 41a and continues on down the deck section 13a. The classifier tank is, of course, filled with water. Since the rear end of the tank is closed, as the reciprocating rakes or raking blades move rearwardly or downwardly, the compression caused thereby produces a pulsation upward through the slot 26, and return motion of the blades produces an opposite pulsation. Thus a jiggling action is produced in or through the slot, since the water has no other escape on the rearward stroke of the blades. They act like a plunger as they approach and depart from the lower vertical end wall 6 of the tank. The tank water level will have achieved somewhat of a super elevation over the level in the pool, the latter being indicated by the broken line A and the former by the broken line B. This condition prevails because of the higher specific gravity of the material in the pool over that of the liquid bath in the classifier tank. Since there is no outlet for liquid in the tank 7 manifestly only a small part of the liquid entering the superposed pool passes into the tank and the bulk of it will overflow the weir 41a. Because of the rapid flow through this pool only those particles will drop out of the flow whose size and weight is sufficient to render them quickly settleable. Thus in this pool there is a very quick segregation or division of the fractions and only the very quickest settling materials will have an opportunity to drop out of the rapid flow. In other words, in this liquid flow, the particles of different sizes will naturally have different trajectories from the point where they pass over the jump baffle 37 to the weir 41a. All of those particles having a trajectory which clears the weir 41a will naturally pass off with the overflow. On the other hand, those whose trajectory is more pronounced, causing them to impinge upon the weir providing member 41 and the baffle 15, will drop through the slot 26 and ultimately settle within the liquid in the classifier tank to the bottom thereof.

In actual practice, there is generally built up a bank of settled sands (indicated by dots on the drawings in Fig. 4) extending from the top of the jump baffle 37 down to the free end of the member 27. When this condition is established it is found that the sands thereafter, even though settling upon the established bank, are carried by the rush of the current down to the lip 13 and flow in sheet formation through the slot 26 into the tank.

Thus, by means of the present classifier apparatus, there is accomplished what may be termed a quick division or segregation of the feed suspension wherein only the heaviest, and therefore quickest settling particles are ejected from a rapidly flowing stream and collected and settled in the main classifier tank from whence they are conveyed as a relatively clean sand product or coarse material.

In a further modification of the invention addi-

tional water may be continuously supplied to the tank bath in order to cause some upflow through the slot 26. This may be conveniently accomplished by means of a suitable liquid supply element which sprays water upon the sands at about the point where they emerge from the liquid in the classifier tank. To this end there is shown in Fig. 1 a pipe or conduit 42 extending transversely through the classifier tank toward the rear thereof and somewhat above the normal liquid level. The pipe 42 is provided with one or more downwardly directed spray nozzles 43. Water under pressure is supplied through pipe 42 and ejected through nozzles 43 in the form of a spray directed upon the sands at about the point where they emerge from the liquid in the tank. As water is continued to be supplied through the conduit 42, since there is no other exit, it will naturally cause an up-current of water through the slot 26 and into the superposed pool, ultimately passing out over the weir 41a. In some operations this upflow will function to carry up undesirable small and intermediate sized particles that may have strayed downwardly through the slot and may also assist, by dilution, the segregation taking place within the pool. In this embodiment the baffle 15 and lip 38 serve to direct the upflow through the slot and tend to establish a uniform flow.

In either form of the invention it will, of course, be understood that the invention is not limited to the precise details of construction shown and described herein. In other words, the essence of the invention resides in providing a classifier apparatus which has means for conveying settled sands upwardly along an inclined bottom, with means in hydraulic communication with the classifier tank for establishing and maintaining a relatively small classification pool so that the feed suspension will pass rapidly through the pool and while so doing undergoes a quick and sharp segregation or fractionation, dropping into the tank only particles of a desired relatively coarse size as one fraction, with substantially all of the finer and intermediate particles as another fraction overflowing from the pool and not being permitted to enter the tank at all. Thus the invention contemplates providing a classifier tank the lower end of which is decked over, the deck having means associated with it for the establishment of a relatively small classification pool. It then contemplates the provision of a slot or slotted opening through the deck reaching to the pool whereby quickly settling material may drop out of the pool, through the slot and into the classifier tank. It is also contemplated that there be means for varying the area of the pool (or the rate of overflow therefrom) in order that adequate control may be exercised over the classification operation. Adjustment of the dimensions or size of the slotted opening may also be provided.

A major factor of this arrangement is that an operator can thus cause separation or segregation of sized fractions of solids at high dilution harmlessly for the extra water used to dilute the feed does not go into the tank where it would complicate dewatering but instead hurdles the slot and passes directly to overflow from the unitary classification pool that is outside of the main tank.

Much stress has been laid on the extent of the classifying pool so that it should be stated that in connection with a classifier that was six feet wide, a pool was used that varied from 17 inches

in length to 28 inches and a slot was used whose length was 3 feet but whose width varied from 4½ to 12 inches. This classifier was used in classifying limestone, and was fed at rates from 55 tons of solids per hour up to over 100 tons per hour. In liquid measure, the feed amounted to about 300 gallons of liquid per minute.

The separation ranged from 6 to 14 mesh.

I claim:

1. In a classifying apparatus in operative combination, a sloping classifying basin adapted for reception of feed of solids in suspension at an upstream entrance and for the discharge of slimes from the downstream exit, having a sloping deck over which there is an unobstructed classifying zone progressively increasing in depth and having an opening therethrough leading from the deep portion of said zone for the gravitational discharge therethrough of coarser solids as sands, means comprising a feed receiving well disposed at the upstream section of the deck having a cross-stream member providing a curtain baffle disposed over the upstream section of the deck and below which is a flow-passage leading downstream from the well; upstanding flow-impeding means disposed downstream of the curtain baffle but upstream from the sands discharge opening adapted for horizontally distributing the feed; a cross-stream overflow member upstanding from the deck and disposed downstream of the opening including vertically positionable weir means over which must flow substantially all of the liquid of the original feed having in suspension certain remaining smaller sized solids leaving the apparatus as slimes; a tank in hydraulic communication with the basin through the medium of said opening and having liquid-confining walls extending upwardly to elevations higher than that of said vertically positionable weir means whereby the tank is adapted for retaining liquid at a level that can rise higher than the elevation of said weir means; and means for removing sands from the tank.

2. An apparatus as defined in and by claim 1 in which the curtain baffle has a vertically adjustable lower portion whereby the flow space below the same can be regulated as to its height.

3. An apparatus as defined in and by claim 1 in which the basin adapted for reception of solids in suspension is in the form of a sloping trough of which the bottom provides the deck over which there is the classifying zone that progressively increases in depth; in which the tank provided for receiving the sands has an inclined floor section sloping in the same general direction as that of the deck of the sloping trough; in which the means for removing the sands from the tank is a reciprocating rake structure operatively disposed over the inclined floor section of the tank; and in which there is a deflector plate depending from the trough deck in the immediate region of the downstream portion of the sand discharge opening and over a region in which rake structure operates.

4. An apparatus as defined in and by claim 1 in which there is a deflector baffle extending downwardly from the bottom of the basin in the immediate region of the downstream edge of the sands discharge opening, and in which the means for removing sands from the tank embodies a sands conveying structure operatively disposed with respect to the tank floor and functional for transferring sands to emergence from the re-

gion near the lower portion of said deflector baffle.

5. A classifying unit for dividing a flow-stream of liquid-solids mixture into slimes and sands and comprising in operative combination a trough having a sloping bottom; means providing as an upstream member a feed-receiving well disposed at the high section of the sloping bottom and embodying a curtain baffle defining the top of a distributing flow passage leading downstream from the lower portion of the feed-receiving well; a cross-stream jump baffle downstream from the feed-receiving well and providing an upper edge over which the flowing liquid-solids mixture trajectory passes after leaving said sands distributing flow passage; which said bottom provides a substantial extent of floor area sloping downwardly and downstream from said jump baffle and has therethrough a sands discharge slot extending transversely of the trough and disposed at the low section of the trough bottom; a vertically-positionable weir extending upwardly from said bottom and disposed downstream with respect to said sands discharge slot and over which weir substantially all of the liquid of the mixture and certain solids thereof which have been classified as to maximum size range must pass from the unit as slimes, the interior of the trough being unobstructed within the liquid-holding space between the jump baffle and the vertically-positionable weir whereby there can follow a horizontal flow of surface liquid from the jump baffle region to and over the positionable weir; a tank having a liquid-tight connection with said trough but disposed so as to have constant hydraulic communication therewith through said sands discharge slot and constructed so as to comprise rising marginal walls reaching to elevations substantially higher than that of the overflow elevation of the vertically-positionable weir for thereby retaining liquid so that the level of such retained liquid can rise substantially higher than that of the slimes when overflowing said weir; and means for removing as sands from said tank the larger solids which have been passed therewith through the said sands discharge passage-way.

6. An apparatus as defined in and by claim 5 in which the cross-stream jump baffle is longitudinally adjustable with respect to the downwardly sloping bottom section of the trough.

7. An apparatus as defined in and by claim 5 in which the cross-stream jump baffle and a movable section of the bottom of the trough are connected and are simultaneously adjustable lengthwise of the trough and in which said movable section has one edge arranged to overlie an edge of said sands-discharge slot in certain positions of adjustment whereby the area of the slot is adjusted according to the adjustment of the jump baffle.

8. An apparatus as defined in and by claim 5 according to which the curtain baffle has a vertically adjustable lower member; the cross-stream jump baffle is adjustable with respect to the trough; and a section of the trough bottom that defines one edge of the slot is adjustable to vary the effective area of the slot.

9. An apparatus for classifying the solids in suspension comprising in operative combination a classifying trough shallow at one end and deep at the other and adapted for the reception of feed of solids in suspension at the shallow upstream entrance end thereof, provided with a cross-stream slot at a lower portion thereof for the

gravitational discharge of coarse solids as sands from the trough, constructed for the discharge of outflowing slimes from the upper portion of the deep end section thereof, and having a deck embodying a sloping floor section that is inclined downwardly in the direction of flow and that extends horizontally in cross-stream direction; a cross-stream end member rising at the deep end of the trough and provided at the top thereof with a slimes overflow weir; means providing a feedwell at the shallow end of the trough and embodying a cross-stream member providing a curtain baffle below which a flow passage leads downstream from the well; a flow distributing means embodying a cross-stream jump baffle positionable along said sloping floor section and having a horizontally-extending upper edge providing a submerged distributing member disposed downstream from the curtain baffle but upstream from the sands discharge slot, the interior of the trough being unobstructed within the liquid-holding space between the jump baffle and the slimes overflow weir whereby there can follow a horizontal flow of surface liquid from the jump baffle region to and over the slimes overflow weir; means for holding the jump baffle in its various adjusted positions with respect to said sloping floor section; a tank in hydraulic communication with the trough through the medium of said slot and having marginal walls rising to elevations substantially higher than that of the slimes overflow weir thereby adapting the tank for retaining liquid up to a level which may rise substantially higher than the elevation of the slimes overflow weir; and means for removing sands from the tank.

10. An apparatus for classifying solids in suspension comprising in operative combination a sloping classifying trough providing a high upstream end and a deep downstream end adapted for the reception of feed of solids in suspension at the upstream end thereof, provided with a cross-

stream slot at a lower portion thereof for the gravitational discharge of coarse solids as sands from the trough, and from which there is a discharge of outflowing slimes from an upper portion of the deep downstream end thereof, the bottom of which trough embodies a fixed deck section sloping downwardly in the direction of flow, extending horizontally in cross-stream direction and over which there is a classifying zone 5 that progressively increases in depth and also a movable deck section positionable with respect to said fixed deck section so as to adjustably define one of the long edges of the slot and thereby the effective area of the slot opening; a cross-stream end member rising within the trough from a region in the vicinity of the deep end of the deck and provided along the top thereof with a slimes overflow weir functionally disposed downstream with respect to the sands discharge slot; means 10 providing a feedwell at the shallow end of the trough and embodying a cross-stream member providing a curtain baffle below which a flow-passage leads downstream from the well; flow impeding and distributing means disposed downstream from the curtain baffle but upstream from the sands discharge slot; a liquid-holding tank in hydraulic communication with the trough through the medium of said slot and having rising liquid-confining structure extending to elevation 15 higher than said slimes overflow weir and thereby adapting the tank for retaining liquid up to a level which may rise substantially higher than the elevation of the slimes overflow weir; and means for removing sands from the tank, 20 the upper interior portion of the classifying zone being left unobstructed whereby the classifying pool normally maintained therein has a continuous horizontal flat surface extending from the shallow upstream section of the trough to the 25 slimes overflow weir.

THEODORE B. COUNSELMAN.
